Attorney

UNITED STATES PATENT OFFICE.

DAVID M. WENGER, OF LEOLA, PENNSYLVANIA.

ROTATIVE AND LOCKING UNIT-SUPPORTING CLOTHES WRINGER AND INCASING
GEAR MECHANISM.

Application filed December 28, 1927. Serial No. 243,132.

This invention is a continuation-in-part of the applications Serial No. 117,114, filed June 19, 1926, and Serial No. 203,191, filed July 2, 1927, and has for its own object the provision of improvements in swinging mechanism for supporting a washing machine wringer, particularly in the means for providing in part swinging housing for the mechanism which imparts forward and reverse motion to the wringer rolls, in any of the multiple positions provided by the swinging mechanism.

An object of this invention is to provide a longitudinal tubular swinging housing containing suitable mechanism for operating the wringer, the tubular housing being provided with a locking means adapted to prevent the housing from a swinging movement, being allowed free and full rotation of the driving shafts and mechanism for operating the wringer at all times.

A further object of this invention is to provide a longitudinal tubular housing constructed of a plurality of parts which may be easily assembled into interlocked relationship, thereby forming a unitary housing.

In this invention, the entire housing within which are located the vertical shaft and horizontal shaft to drive the wringer, as well as the necessary gearing, is made up of approximately a tubular hollow casing adapted to swing in either direction on suitable supporting brackets, the reversing gearing of the two tooth-faced element type preferably being fastened to an extended portion of the vertical shaft.

A further object of this invention is to provide a locking mechanism suitably fastened to a washing machine element and adapted to engage with a gear or ratchet fixed on the swinging mechanism.

Another object of this invention is to provide a longitudinal unitary oscillatory wringer support and gear housing which is adapted to be held in operable relationship to the main body portion of the washing machine by means of suitable bearing brackets and supporting elements rigidly attached to the main body portion, the locking mechanism being also attached thereto.

Other objects of this invention will appear from the following detailed description of

the device and as disclosed in the single sheet of drawings which is herewith made a part of this application.

55

In the drawings—

Figure 1 illustrates a front elevational view of the device, disclosing the tubular housing in section and the interlocking and swinging mechanism in assembled relationship thereto.

60

Figure 2 represents an end view of the extension arm for receiving the wringer and disclosing in broken lines various positions into which the arm may be swung; also showing the housing portion for receiving parts of the shaft driving mechanism and a removable cap portion therefor.

65

Figure 3 illustrates a cross-sectional view of Figure 1, taken along line 3—3.

Figure 4 represents a cross-sectional view of Figure 1 taken along line 4—4.

The rotative locking and swinging mechanism for supporting a clothes wringer, according to this invention, is adapted to be driven from any suitable source of power through a drive shaft 1, which is adapted to have mounted and keyed to its upper end a mitre gear 2, which engages with a co-operating gear member 3, suitably keyed to shaft element 4. The shafts 1 and 4, according to this invention, are enclosed in a housing constructed preferably of two main portions 5 and 6, the portion 5 of the housing being rotatably supported at its lower end 7 within a housing portion 8 made of any suitable material such as metal, and adapted to be fastened firmly by means of machine bolts 9 and 10, or otherwise, to a supporting frame member 11 for the washing tub 12. As an additional means for supporting the housing member 5 in proper relationship to the tub 12 and frame 11, a bracket portion 13 is adapted to be firmly attached to the frame member 11 or other suitable position, by means of a machine screw 14, the housing portion 5 being adapted to slidably extend through an opening 15 of the bracket 13. The upper portion 6 of the housing is adapted to be formed having an arm extension 16 at approximately right angles thereto for receiving the shaft member 4 in rotatable relationship thereto. The portion 6 of the housing is adapted to be brought into interlocked relationship with section 5 of the housing by

75

80

means of a sleeve portion 17 integrally formed therewith and adapted to extend a suitable distance within and adjacent to the inner surface of the housing member 5, thereby providing a firm and adjacent connection between the two portions 5 and 6 of the housing and providing thereby a unitary housing for receiving the shaft members 1 and 4. The outer or free end of the swinging arm portion 16 of the housing is provided with a suitable plate member 18 integrally formed therewith for attachment to a clothes wringer of the ordinary type, provision being made within the arm portion 16, as at 19, for receiving the driving shaft extension 20 from the clothes wringer. The mitre gear members 2 and 3 are adapted to be enclosed within an enlarged section 21 of the housing and, for the purpose of providing easy access to the gears 2 and 3, it is preferred that the housing section 21 be provided with a removable cap portion 22 which may be adjusted in attached relationship to the housing section 21 by any suitable means, such as threaded portions 23, or otherwise, the cap portion 22 being formed so that it may be removed from the housing or replaced with the least possible difficulty whenever desired.

The housing comprising the member portions 5 and 6 is adapted to pivot or swing upon the bracket or housing portion 8, and the lower end 7 of the housing may be provided with a bearing section 24 integrally connected with the housing portion 5 or otherwise in order to aid in maintaining the shaft 1 in proper vertical alignment in co-operation with the bearing section 25 on the portion 6 of the housing and upon which the mitre gear 2 is adapted to be supported in rotatable relationship thereto. The supporting bracket 8 will keep the housing portion 5 from slipping downward, while the flanged notched member 26 will aid to keep the housing portion 5 from moving up, it being understood that the flanged member 26 is adapted to be firmly keyed to the housing member 5 by means of a set screw 27.

The locking means for retaining the housing, comprising the sections 5 and 6, in a desired position comprises in general a flanged member 26 having a plurality of notches therein 28, 29, 30 and 31 arranged peripherally thereof, the flanged member being securely fastened by means of a set screw 27 to the housing portion 5 and entirely enclosed within the housing or bracket portion 8. A cooperating interlocking element 32 is arranged in slidible position within the bracket and housing portion 8 in such a manner that, when a notched portion 33 in the sliding member 32 is directly opposite the flanged member extension 26, the housing portion 5 may be easily revolved into the desired position and, when the notched portion 33 is out of alignment with the notched por-

tion 36, the sliding member 32 will be drawn by a spring member 34 into one of the notched elements 28, 29, 30 and 31, and locked in the flanged member 26, thereby securely locking the housing in the desired position. 70

In order to accelerate the sliding movement of the member 32, a suitable handle portion 35 is connected thereto and extends to a convenient position, as at 36 for manually operating, the rod 35 being slidably arranged in 75 the guide bracket 13 or other suitable member attached to the tub or supporting frame thereof. The spring 34 is positioned preferably under the bracket 13 in such a manner as to aid in pulling, when desired, the member 80 32 in engagement with the notches on the flanged member 26.

The bracket or housing member 8 is constructed in such a manner that it will provide an approximate covering and protection for 85 the slideable member 32 and the flanged element 26. In order to gain easy access to the housing 8, it is preferred to provide a cover portion 37 adapted to be removably attached to the bracket or housing portion 8 by means 90 of screws 38 or otherwise.

The bearing member 24 within the lower end of the housing portion 5 is adapted to be turned to a tight fit for the inside periphery of the tubular portion 5 and then pressed into 95 the lower end thereof. Both the alignment bearings 24 and 25 may be easily bored with a long drill after the portions 5 and 6 are rigidly fastened together by means of the sleeve element 17, thereby insuring correct 100 alignment. The portion 5 of the housing is preferred to be made of seamless tubing, therefore, insuring a member having no peripheral openings. 105

In operation, this invention provides an 105 efficient and inexpensive means for swinging clothes wringers to the right or left and locking it in any desired position, the wringer in this invention being attached to the pivotally mounted housing, while the driving shafts 110 and gears therein are arranged to receive a reversing motion through suitable gearings attached thereto. The interlocking portion located at the base of the housing is encased, in this invention, so that it will be protected 115 from excessive moisture and the like. The form of the housing or encasement for the interlocking elements may be of any desirable type, one modification being herewith described and disclosed in the drawings. 120

In this invention, it is to be noted that the extending shaft 20 of the clothes wringer is adapted to be flexibly joined to the shaft member 4 by means of a suitable coupling member 19, and that two shafts meet properly at the inside of the coupling. The construction as herein set forth clearly defines a rotative unit of interlocked portions 5, 6 and 16, forming a continuous encasement for receiving the mechanism, such as the shaft por- 130

tions 1 and 4, together with gearing 2 and 3, having means for locking the unit in a plurality of positions, the housing being provided with openings through which it is possible to obtain access for drilling holes, facing and inserting the shaft portions and gearing.

It is to be understood that alterations and substitutions may be made in the above disclosure, including the drawings within the scope of the appended claims, without affecting the merits of this invention.

What I claim is:

1. In a rotative unit of the character described, a continuous housing for vertical and horizontal shafts, the vertical shaft having a gear at one end for cooperating with a gear connected to the horizontal shaft, the continuous housing having an enlarged section of spherical formation for receiving the gearing in meshed relationship therein, an opening in the enlarged section of the housing for access to the gearing, and a detachable cover for the opening, bearings within the housing for properly aligning the shafts therein, means at the lower end of the housing for locking the unit at predetermined points in its rotation, and a protective covering for the locking means.

2. In a rotative unit of the character described, a continuous housing for vertical and horizontal shafts, the vertical shaft having a gear at one end for cooperating with a gear connected to the horizontal shaft, the continuous housing having an enlarged section of spherical formation for receiving the gearing in meshed relationship therein, an opening in the enlarged section of the housing for access to the gearing, and a detachable cover for the opening, bearings within the housing for properly aligning the shafts therein, a flanged member attached to the lower end of the housing having a plurality of notches therein for receiving a cooperative locking member.

3. In a rotative unit of the character described, a continuous housing for vertical and horizontal shafts, the vertical shaft having a gear at one end for cooperating with a gear connected to the horizontal shaft, the continuous housing having an enlarged section of spherical formation for receiving the gearing in meshed relationship therein, an opening in the enlarged section of the housing for access to the gearing, and a detachable cover for the opening, bearings within the housing for properly aligning the shafts therein, a flanged member attached to the lower end of the housing having a plurality of notches therein for locking the housing in any desired position, a supporting member for the housing, a protective covering for the flanged member attached to the supporting member.

4. In a rotative unit of the character described, a continuous housing for vertical and horizontal shafts, the vertical shaft having a

gear at one end for cooperating with a gear connected to the horizontal shaft, the continuous housing having an enlarged section of spherical formation for receiving the gearing in meshed relationship therein, an opening in the enlarged section of the housing for access to the gearing, and a detachable cover for the opening, bearings within the housing for properly aligning the shafts therein, a flanged member attached to the lower end of the housing having a plurality of notches therein for locking the housing in any desired position, a supporting member for the housing, a protective covering for the flanged member attached to the supporting member, an element slidably arranged within the protective covering for cooperating with the locking flanged member.

5. In a rotative unit of the character described, a continuous housing for vertical and horizontal shafts, the vertical shaft having a gear at one end for cooperating with a gear connected to the horizontal shaft, the continuous housing having an enlarged section of spherical formation for receiving the gearing in meshed relationship therein, an opening in the enlarged section of the housing for access to the gearing, and a detachable cover for the opening, bearings within the housing for properly aligning the shafts therein, locking means attached to the lower end of the housing, a protective covering for the locking means, the continuous housing consisting of upper and lower portions securely connected together, the upper portion having an arm member extending at right angles to the lower portion, the outer end thereof being provided with a suitable plate member for receiving a wringer.

6. In a device of the class described, a main frame, a hollow bracket attached to the frame, a continuous housing rotatively mounted in the hollow bracket, locking means within the hollow bracket for holding the continuous housing in any desired position.

7. In a device of the class described, a main frame, a hollow bracket portion attached to the frame, a continuous housing rotatively mounted in the hollow bracket, a notched flanged member keyed to the continuous housing within the bracket, a cooperating member slidably arranged within the bracket for interlocking with the notched portions of the flanged member.

8. In a device of the class described, a main frame, a hollow bracket portion attached to the frame, a continuous housing rotatively mounted in the hollow bracket, a notched flanged member keyed to the continuous housing within the bracket, a cooperating member slidably arranged within the bracket for interlocking with the notched portions of the flanged member, a lever element for operating the sliding member.

9. In a device of the class described, a main

frame, a hollow bracket portion attached to the frame, a continuous housing rotatively mounted in the hollow bracket, a notched flanged member keyed to the continuous housing within the bracket, a cooperating member slidably arranged within the bracket for interlocking with the notched portions of the

flanged member, a lever element for operating the sliding member, additional bracket means for holding the continuous housing in rotative relationship thereto. ¹⁰

In testimony whereof I affix my signature.

DAVID M. WENGER.
